GEORGE C. WORTHINGTON, OF ELYRIA, OHIO, ASSIGNOR TO THE WORTHINGTON BALL COMPANY, OF ELYRIA, OHIO, A CORPORATION OF OHIO

METHOD OF MAKING PLAYING BALLS

Application filed November 10, 1927, Serial No. 232,449. Renewed November 12, 1931.

This invention relates to a method of making playing balls, especially golf balls, and to such ball itself.

As is well known, virtually all golf balls are made at the present time by winding rubber thread or tape around the center to form what is known as the core. The core constitutes the major part of the ball and presents an outer, generally spherical surface composed of winding turns of rubber thread or tape crossed over each other promiscuously. There are many interstices among the crossed overlapping threads. On top of the core the cover is formed. The duties of the cover are quite onerous. It must confine the core; it must yield to the blows without unduly impairing the flight distance of the ball; it must resist great abuse and maintain the color and the marks on the ball. The connection between the cover and the core should be such as to maintain the two in close connection during a most severe usage which includes the deformation of the ball under the impact of the club and the ground. In addition to all these things, the material in the cover must be enduring and protect the core from the weather and from water, etc.

The objects of this invention are to produce a ball and a process for making a ball having a more durable and more compact cover, and which cover it is substantially impossible to loosen from the core even in the most severe usage to which the ball is submitted; to produce a ball which will fly farther under the impact of the club; to reduce the necessary cover thickness; to produce a ball using less cover material, which will therefore be more economical.

These and other objects of my invention will be better understood from particular descriptions thereof which will follow.

Fig. 1 illustrates a core of a golf ball composed of rubber thread wound under tension upon a center;

Fig. 2 illustrates the core after it has been subjected to a first treatment;

Fig. 3 illustrates the core after it has been submitted to a second step in the treatment;

Fig. 4 illustrates a sheet used in forming a so-called thin half shell; and

Fig. 5 illustrates one of these sheets folded up into a half shell.

The core is made up in the regular way by winding rubber thread or tape under tension upon the center and when completed consists of a sphere presenting an outward surface consisting of the thread or tape wound in turns promiscuously over each other and containing recesses among the winding. I apply to the core thus formed cover stock comprising a mixture which is composed of such a gum as balata, gutta percha or other bastard gum which has been dissolved in a solution of benzol or some other suitable hydrocarbon, and which is in a plastic state when applied. The balata, gutta percha or other bastard gum which is used is preferably refined beforehand. A preferred percentage of such a mixture consists of a quarter of a pound of such gum to a quart of benzol. The preferred way of applying this material to the core is to place some of it in the hands of an operator who rubs it into the surface of the core, distributing it uniformly over the surface, in the presence of a draft of air which may be created by a fan adjacent the hands of the operator, the current of air from the fan drying the hydrocarbon gum solution as it is applied. A very thin layer of the hydrocarbon gum solution is thus applied. The thickness of this layer may be varied, but a uniform layer of $\frac{1}{2}$ -inch is suitable and perhaps preferable. When thus dried the hydrocarbon-gum mixture adheres to the rubber tape, sealing the contiguous portions of the tape together.

A very close union between the outer portions of the core themselves and between the layer of hydrocarbon-gum thus deposited on the outer surface of the core is thus made. This layer of hydrocarbon-gum material forms the first layer of the cover and serves to firmly unite the cover with the core, and in such a way that adjacent sections of the cover and the core follow each other faithfully even during the most severe deflections.

The core with the first layer of the cover thus formed on the same, as has been described, is then dipped into a hydrocarbon-gum material such as has already been de-

scribed as forming the first layer of the cover. Each time that the core is dipped a stratum of the material adheres to the outer surface thereof. The dipping is continued until the thickness of the cover is increased to the desired extent. The cores may be mounted upon racks by pins inserted in the cores and connected to the rack, and large numbers of the cores may be dipped at the same time into the solution. The number of dippings may vary to suit the varying conditions which may exist. Each time the ball is dipped a new stratum is formed. This second addition to the cover is preferably about $\frac{1}{16}$ of an inch thick.

The cores with the first two layers of the cover thus placed on them are then thoroughly dried. The preferred way to dry them is to place them in a drying room for ten days or two weeks.

After the drying is completed, the third and last layer of the cover is placed upon the ball. This is done by forming two thin half shells of a suitable cover stock. I prefer to use refined balata, and to form the half shells by cutting discs of a suitable size out of a thin sheet of balata. The best size for the disc is about three inches in diameter. I then cut two radial slits, about one inch and a quarter in length each, on the same diameter so as to permit the formation of the half shells. These discs are illustrated in Fig. 4 and the half shell just described in Fig. 5. Two or more of these half shells are then applied to the ball containing the first two layers of the cover, and the ball with the half shells is placed in a mold which is submitted to the desired heat and pressure. Under the heat and pressure the half shells merge with the second layer of the cover so that the shells and second layer become a unitary cover connected with the core by the layer of the hydrocarbon-gum solution applied to the surface of the naked core, as I have described. The desired markings are placed on the ball in the mold.

A ball having a homogeneous cover integral with the core results. A cover thus formed, is singularly free from defects. Each portion of the cover is substantially as strong and as durable as all the other portions. The formation of flaws, fissures or other such defects is in such a cover, readily prevented. Because of the homogeneity and the uniformity of the cover, it can be made thinner than the ordinary cover of a golf ball which, owing to possible defects, must be made thick so as to contain a certain safety factor. Making the cover thin in this way not only economizes materials, but it lengthens the flight of the ball under the impact of the club because there is not so much cover to deflect. The inner layers of the core, of course, are held in position by the tension of the outer layers, and the outer

layers of the core are held in position by the first layer of the cover. Under no circumstances can the core separate from the cover or can the core start to unwind, which it has a tendency to do owing to the fact that the rubber thread or tape is under tension and tends to contract if loosened. The process presents the further advantage of insuring a cover made not only of the best material, but of the best material uniformly applied. All foreign substances can be excluded from materials applied in the manner in which the materials in this cover are applied.

I have seen fit to describe only one embodiment of my invention in this application, using generic descriptions of certain of the features and steps. It will be understood that I am not limited to this particular embodiment and to the particular features and steps which I have described for I contemplate variations in both the features and steps within appropriate range of equivalency.

I claim:

1. The method of making a playing ball which consists in forming a substantially spherical core by winding rubber thread or tape upon itself leaving recesses among the turns at the surface, applying at least one relatively thin layer of a plastic cover stock solution to the exterior of the core and forcing the same into the recesses thereof, drying the said cover stock layer, then dipping the resulting ball a plurality of times into a plastic solution of cover stock to add at each dipping an additional thickness of cover stock, drying the ball, and then wrapping thin layers of sheet cover stock about the ball, subjecting the same to heat and pressure and merging the parts of the stock cover together to form a complete integral cover.

2. The method of making a playing ball which consists in forming a substantially spherical core by winding rubber thread or tape upon itself leaving recesses among the turns at the surface, applying at least one relatively thin layer of a plastic cover stock solution to the exterior of the core and forcing the same into the recesses thereof, drying the said cover stock layer, then dipping the resulting ball a plurality of times into a plastic solution of cover stock to add at each dipping an additional thickness of cover stock, drying the ball, forming sheet cover stock into a plurality of cup-like cover elements, distributing them around the ball to enclose the same therewithin, subjecting the cover elements and the ball to heat and pressure and merging the parts of the stock cover together to form a complete integral cover.

3. The method of making a playing ball which consists in forming a substantially spherical core by winding rubber thread or tape upon itself leaving recesses among the turns at the surface, applying at least one relatively thin layer of a plastic cover stock

solution to the exterior of the core and forcing the same into the recesses thereof, drying the said cover stock layer, then dipping the resulting ball a plurality of times into a plastic solution of cover stock to add at each dipping an additional thickness of cover stock, drying the ball, forming sheet cover stock into a plurality of discs having radial slits therein, folding the discs into cup-like cover elements with portions of the sheet adjacent the slits overlapping, distributing the cover elements around the ball to enclose the same therewithin, subjecting the same to heat and pressure and merging the parts of the stock cover together to form a complete integral cover.

4. The method of making a playing ball which consists in forming a substantially spherical core by winding rubber thread or tape upon itself leaving recesses among the turns at the surface, applying at least one relatively thin layer of a plastic cover stock solution to the exterior of the core and forcing the same into the recesses thereof, drying the said cover stock layer, then applying to the resulting ball a plastic solution of cover stock to add an additional thickness of cover stock, drying the ball, and then applying a thin layer of sheet cover stock to the ball, subjecting the same to heat and pressure while merging the parts of the cover stock together to form a complete integral cover.

5. The method of making a playing ball which consists in forming a substantially spherical core by winding rubber thread or tape upon itself leaving recesses among the turns at the surface, applying at least one relatively thin layer of a plastic cover stock solution to the exterior of the core and forcing the same into the recesses thereof, drying the said cover stock layer, then applying to the resulting ball a plastic solution of cover stock to add an additional thickness of cover stock, drying the ball, forming sheet cover stock into a plurality of cup-like cover elements, distributing them around the ball to enclose the same therewithin, subjecting the cover elements and the ball to heat and pressure and merging the parts of the stock cover together to form a complete integral cover.

6. The method of making a playing ball which consists in forming a substantially spherical core by winding rubber thread or tape upon itself leaving recesses among the turns at the surface, applying at least one relatively thin layer of a plastic cover stock solution to the exterior of the core and forcing the same into the recesses thereof, drying the said cover stock layer, then applying to the resulting ball a plastic solution of cover stock to add an additional thickness of cover stock, drying the ball, forming sheet cover stock into a plurality of discs having radial slits therein, folding the discs into cup-like cover elements with portions of the sheet ad-

jacent the slits overlapping, distributing the cover elements around the ball to enclose the same therewithin, subjecting the same to heat and pressure and merging the parts of the stock cover together to form a complete integral cover.

7. As an article of manufacture, a golf ball comprising a substantially spherical core having a winding of rubber thread or tape wound upon itself with interstices among the turns of the surface, a plurality of successive relatively thin layers of dried plastic cover stock solution superposed thereover and lining and substantially filling the interstices thereof, and a thin layer of sheet cover stock wrapped thereover and merged therewith.

8. As an article of manufacture, a golf ball comprising a substantially spherical core having a winding of rubber thread or tape wound upon itself having interstices among the turns of the surface, a plurality of successive relatively thin layers of dried plastic cover stock solution superposed thereover and lining and substantially filling the interstices thereof, and a cover formed from a plurality of cup-like sheet cover stock elements, distributed around and upon the ball enclosing the same therewithin.

9. As an article of manufacture, a golf ball comprising a substantially spherical core having a winding of rubber thread or tape wound upon itself having interstices among the turns of the surface, a plurality of successive relatively thin layers of dried plastic cover stock solution superposed thereover and lining and substantially filling the interstices thereof, a cover formed from a plurality of sheet cover stock discs having radial slits therein, the discs comprising cup-like cover elements with portions of the sheet adjacent the slits overlapping and distributed about the ball enclosing the same therewithin and merged therewith and forming a complete integral cover.

In testimony whereof I hereunto affix my signature this 8th day of November, 1927.

GEORGE C. WORTHINGTON.
